(57) **CLAIM**

The ornamental design for a stainless steel toilet, as shown and described.

DESCRIPTION

FIG. 1 is a perspective view showing the top right side and front of a stainless steel toilet including a tank showing our new design;

FIG. 2 is a top view thereof;

FIG. 3 is a front view thereof; and,

FIG. 4 is a right side view thereof of which a mirror image would be a left side view thereof.
